CLAIM

The ornamental design for a ceiling fan, as shown and described.

DESCRIPTION

FIG. 1 is a top perspective view of a ceiling fan, showing my new design;

FIG. 2 is a top view thereof;

FIG. 3 is a bottom view thereof;

FIG. 4 is a front view thereof;

FIG. 5 is a right side view thereof;

FIG. 6 is a left side view thereof; and,

FIG. 7 is a rear view thereof.

The broken lines illustrate portions of the ceiling fan that form no part of the claimed design. Jagged break lines represent broken away symbols and form no part of the claimed design. The appearance of any portion of the ceiling fan blades between jagged break lines forms no part of the claimed design.
